(57) **CLAIM**

The ornamental design for an anti-collision box for pressure gauge of bead booster as shown and described.

DESCRIPTION

FIG. 1 is a perspective view of an anti-collision box for pressure gauge of bead booster showing my new design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing of bead booster is included for the purpose of illustrating environmental structure while all other broken lines illustrate portions of the anti-collision box; the broken lines form no part of the claimed design.
